(57) **CLAIM**

The ornamental design for a tread of an automobile tire, as
shown and described.

DESCRIPTION

FIG. 1 is a perspective view of a tread of an automobile tire
showing my design;

FIG. 2 is a front view thereof;

FIG. 3 is a top view thereof;

FIG. 4 is a right side view thereof;

FIG. 5 is a fragmentary enlarged front view showing the
details of the tread portion thereof; and,

FIG. 6 is a section view taken along line 6-6 in FIG. 5.
In the drawings, the intermediate and dark stippled shading
correspond to the groove depths shown in FIG. 6.

The broken lines in the drawings show portions of the tire
that are not being claimed, and thus form no part of the
claimed design.
